MULTIPLE CONDUCTOR FUSE

Application filed May 20, 1930, Serial No. 453,902, and in Germany May 24, 1929.

Our invention relates to fuses and particularly to fuses for high-voltage circuits.

One object of our invention is to provide a unit fuse structure comprising a plurality of 5 chambers and a plurality of corresponding fusible elements which are connected together in parallel relation.

Another object of our invention is to provide a fuse structure, of the above-mentioned 10 type, having two casings that are concentrically disposed and are provided with closure members that are independently releasable from each other and from the casings.

15 A further object of our invention is to provide a fuse structure, of the above-designated type, with fusible elements of different current-carrying capacities that shall be ruptured in sequence and in such order that the 20 element of greater resistance shall be inserted in shunt relation to the arc.

Our invention will best be understood by referring to the following specification, in conjunction with the accompanying drawing,

25 wherein:

Figure 1 is a view, in sectional elevation, of a fuse structure embodying our invention.

Fig. 2 is a fragmentary view, in sectional elevation, of a fuse structure embodying a 30 modified form of our invention.

Our invention comprises, in general, an insulating casing 1 having a closure or cap 2 and a ferrule 3, attached to its respective ends to constitute terminal members for connecting the fuse in an electrical circuit.

Fuses for protecting high-voltage circuits, 40 have been employed heretofore which comprised a plurality of conductors of different resistance respectively located in separate closing tubes and connected in parallel relation to a single conductor exterior to the tubes. A fuse of this type was found to be particularly effective for interrupting a large amount of energy under short-circuit conditions and 45 could be made relatively small and considerably more effective, when enclosed within a single structure.

The successful operation of a fuse of this 50 type in a circuit having a very high short-circuit current, results because fusion of the

main conductor is effected with practically no arcing on account of being bridged by the shunt conductor and because the final interruption of the circuit by the shunt conductor is rendered relatively harmless by the inherent resistance of the conductor which operates as a protective resistor.

Upon rupture of the fusible elements connected in a circuit in which a large amount of energy is present, a considerable amount of 60 gas is evolved that is utilized in our fuse structure for aiding the extinguishment of the arcs, in a manner that will be explained more fully hereinafter.

A casing 4 is disposed within the casing 1 65 and is retained in concentric relation thereto by a washer 5 that is attached to its lower end. The washer 5 abuts against the end of the casing 1 and prevents the longitudinal movement of the casing 4, relative to the casing 1, 70 when pressures are developed within it. A fusible element 6 is disposed within the casing 4 and is retained in central relation thereto by a washer 7 that abuts against the end of the casing and is provided with a central 75 opening through which the fuse wire extends. The enclosing cap 2 is screwed upon the threaded end of the casing 1 to retain the end of the fusible element 6 against the washers 7 and 5 and clamp the washers 5 and 7 against 80 the casings 1 and 4, respectively.

The end of the casing 1 that is provided with the ferrule 3, has an extension 8 of conducting material associated therewith that is provided with an inwardly sloping surface 9. A contact member 11 engages the surface 9 and is retained in fixed relation to the casing 4 because of its frictional engagement with that surface. The contact member 11 is employed as a releasable closing 85 member for the casing 1 and also as a conducting contact member to which a fusible element 12 is attached by means of a screw 13. The other end of the fusible element 12 90 is attached to the washer 5 by a screw 14. 95 The fusible element 12 is wound about the tube 4 and is of considerably greater length than the fusible element 6.

The fusible element 6 is made of copper, silver or like material of high conducting 100

properties, while the fusible element 12 is made of tungsten, molybdenum or like material that offers relatively high resistance to current flow.

5 A second contact member 15, in the form of a cap, as illustrated in the drawing, is associated with the open end of the tube 4 in releasable current-carrying engagement with the contact member 11. The contact member 15 is employed as a closure member for the tube 4 and also as a terminal member for the fuse element 6 that is soldered thereto, as at 16. The releasable connection between contact members 15 and 11 permits separation of them upon the rupture of the fusible elements 6 and 12, respectively, and the escape of the accumulated gas from within the casing 4, before the gases in the casing 1 have generated a sufficient pressure to release the contact member 11.

20 The operation of our fuse device will now be described: Upon the occurrence of a short-circuit condition in the circuit in which the device is in series relation, the fusible element 6, which is carrying the greater portion of current, because of its higher conductivity, will rupture first. The arc established within the casing 4 will generate gases because of the vaporization of the fusible element 6 and the decomposition of the material of the casing 4. This material is preferably fibre, although any other material that liberates un-ionized gases, when decomposed by an arc, may be substituted. The un-ionized gases are beneficial in cooling the arc stream and providing nuclei upon which the ions in the arc stream recombine to form neutral layers. When the volume of the gas within the casing 4 generates a predetermined pressure, the cap 25 15 over the end thereof is blown off, and the gases and the arc will be blown from within the casing.

Because of the greater resistance to current flow offered by the arc within the casing 4 than that offered by the fuse element 12, the latter will be ruptured and an arc will be established within the casing 1 exterior to the casing 4. The arc within the casing 1 will effect a generation of gas similar to that heretofore referred to relative to the arc established within the casing 4. When the volume of gas and the pressure thereof reach a predetermined amount, the contact member 11 will be blown from the end of the casing 1, and the gases and the arc within the casing will be ejected from it. In passing out through the arc path, the un-ionized gas will effect a rapid deionization thereof that will prevent the arc from re-striking.

From the foregoing description it will be apparent that the frictional engagement between the contact member 15 and the contact member 11, and that between the contact member 11 and the extension 8 should 65 be such that the release of the member 15

will require less effort than that required to release the contact member 11.

A more rapid deionization of the arc stream may be had by providing insulating pellets 17 within the casings 1 and 4 that cool and divide the arc and increase the rate of recombination of the ions of the arc path.

It is apparent that the ferrule 3 may be positioned away from the end of the casing 1, as shown in Fig. 2, and a contact member 18 75 may be arranged to extend downwardly into frictional engagement with the ferrule 3, as illustrated in this figure. In this construction, when the contact members 15 and 18 are expelled from the ends of the casings 1 80 and 4, the ferrule 3 will be insulated from the escaping gases and the arc by the casing 1 that extends beyond the ferrule.

It will thus be seen that I have provided a unit fuse structure that combines the operation of two independent fuse devices which are connected in parallel relation in a circuit. The casings for the fusible elements of different resistance are closed by conducting members that are independently blown from 90 the ends of the casings as the fusible elements are ruptured, in sequence, in the presence of a short-circuit current. The initial arc has a greater portion of the current shunted therefrom by the fusible element of greater 95 resistance that is in shunt relation thereto and, by blowing the arcs and the contact closure members from the casings, both of the arcs are extinguished. By passing the un-ionized gas, that is evolved by the decomposition of the material of the casings, through the arc path as the gas and the arc are blown from within the casing, the arcs are prevented from re-striking.

While we have described and illustrated 105 only two embodiments of our invention, it is apparent to those skilled in the art that many changes, additions, omissions and substitutions may be made therein without departing 110 from the spirit and scope of our invention, as set forth in the accompanying claims.

We claim as our invention:

1. In a fuse structure, the combination with a plurality of concentrically associated tubes supported in fixed relation to each other, of independent fusible elements positioned in the respective tubes and connected in parallel relation, said elements being ruptured successively upon the occurrence of an overload condition, and separable conducting closure members for the respective tubes connected in circuit with their respective fuse elements, the closure member connected to the fusible element which is first ruptured being separable independently of the other 120 closure member.

2. In a fuse structure, the combination with two concentrically associated chambers, of a fusible element calibrated in accordance 125 with the rating of the fuse structure and dis-

posed within one of said chambers, a fusible element presenting a higher resistance to current flow than the first said element and disposed in the other said chamber and separable conducting closure members for said chambers connected to their respective fusible elements, the closure member for the chamber containing the first-mentioned fusible element being connected in circuit through the other closure member and separable independently thereof, said other closure member being arranged to remain in circuit after removal of the first closure member.

3. A fuse structure including two concentrically associated chambers, a fusible element in each chamber, releasable covers for the respective chambers conductively joined to each other and to the fusible elements, and means for retaining one of said covers on its associated chamber as the other of said covers is released from its chamber.

4. The combination with a main and an auxiliary fusible element of different current-carrying capacities that are enclosed in separate concentrically disposed chambers, of separate contact members closing the respective chambers and conductively joined to the respective fusible elements thereof, the said contact members being independently releasable from their associated chambers when actuated by the pressure developed therein by the rupture of the corresponding fusible element.

5. The combination with a main fusible element and an auxiliary fusible element which offers considerable resistance to current flow, said elements being enclosed in separate concentrically disposed chambers, of separate contact members for closing the respective chambers and conductively joined to the respective fusible elements, the said contact members being independently releasable from their associated chambers in sequence, as the fusible elements are ruptured.

6. In a fuse structure, the combination of two chambers each containing a fusible element, said elements being connected in parallel relation and being fusible successively upon the occurrence of an overload condition, a separable conducting member closing the chamber containing the element last to be fused and connected to said element, and a second conducting member closing the chamber containing the element first to be fused and connected to said element, the second conducting member being connected in circuit through the first conducting member and being separable independently thereof.

7. In a fuse structure, the combination of two tubular members arranged in telescopic relation and providing an inner chamber and an annular chamber encompassing the inner chamber, fusible elements disposed in said respective chambers and connected in paral-

lel relation, the element in the inner chamber being ruptured first and the element in the annular chamber second upon the occurrence of an overload condition, a conducting member for closing the annular chamber and connected to the fusible element therein, and a second conducting member for closing the inner chamber and connected to the fusible element therein, the second conducting member being connected in circuit through the first conducting member and separable independently thereof, whereby, upon the occurrence of an overload condition, the second conducting member may be blown out to permit extinguishment of the arc created by the fusible element in the inner chamber while the other fusible element remains in circuit through the first conducting member.

In testimony whereof, we have hereunto subscribed our names this 25th day of April, 1930.
